DESIGN FOR A TOY FROG

Philip Boyajian, New York, N. Y.

Application April 7, 1944, Serial No. 113,169

Term of patent 3½ years

(Cl. D34—15)

To all whom it may concern:

Be it known that I, Philip Boyajian, a citizen of the United States, residing at New York city, in the county of New York and State of New York, have invented a new, original, and ornamental Design for a Toy Frog, of which the following is a specification, reference being had to the drawing, forming a part thereof.

In the drawing:

Fig. 1 is a plan view of a toy frog showing my new design.

Fig. 2 is a rear elevational view.

Figs. 3 and 4 are side elevational views showing my toy frog in different positions which it assumes when pulled along the floor.

I claim:

The ornamental design for a toy frog, substantially as shown.

PHILIP BOYAJIAN.
